UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

STATIC-ELECTRICITY DISSIPATOR FOR PAPER WEBS OR SHEETS.

1,183,338.

Specification of Letters Patent.

Patented May 16, 1916.

Application filed May 3, 1913. Serial No. 765,313.

To all whom it may concern:

Be it known that I, HOWARD M. BARBER, a citizen of the United States, and resident of Stonington, in the county of New London 5 and State of Connecticut, have invented a new and useful Improvement in Static-Electricity Dissipators for Paper Webs or Sheets, of which the following is a specification.

10 My invention relates to improvements in static electricity dissipators for paper webs or sheets, and is directed to that type of dissipator or neutralizer in which the electricity is removed from the web by slightly 15 moistening the same, also providing a static discharge through a moistened wick contact.

20 The object of this invention is to provide mechanically operated means, such as a governor, under control of the speed of the press, whereby the dissipator and web are brought into coaction when the web is running and out of coaction when the web is still.

25 This invention is directed more particularly to mechanically operated means for moving the web into and out of contact with the moistener of the dissipator, while my co-pending application filed of even date 30 herewith, Serial No. 765,312 is more particularly directed to mechanically operated means for moving the moistener of the dissipator into and out of contact with the web. If the web be left in contact with the 35 moistener of the dissipator when the web is still, the paper would become saturated to such a degree as to materially weaken or break it. This invention is directed to means for avoiding this trouble.

40 A practical embodiment of the invention is represented in the accompanying drawings in which,

45 Figure 1 represents in side elevation so much of a folding machine as will give a clear understanding of the construction, location and operation of the several parts of my static electricity dissipator, the parts being shown in full lines in the position which they assume when the web is running 50 and in dotted lines in the position they assume when the web is still, and Fig. 2 is a transverse section taken in the plane of the line A—A of Fig. 1.

The web 2 is shown as passing around a series of rolls 3, 4, 5, 6, on its way from 55 the printing press, not shown, to the formers 7 of the folding machine. The rolls 3 and 4 are located upon the same side of the web 2, and are mounted in oppositely arranged pairs of arms 8, 9, of a compensating lever pivoted at 10 in the main frame 11. The compensating lever is so mounted that the rocking of the lever will move the positions of the rolls 3 and 4 to change the path of the web 2, without changing its 60 65 tension.

The moistening wick of the dissipator is denoted by 12, and its fountain by 13, which fountain is supported in the main frame 11. Liquid is supplied to the fountain 13, from 70 a stationary reservoir 14 mounted on a bracket 15 secured to the main frame 11, through a feed pipe 16 having a suitable controlling cock 17.

75 Automatically operated means under the control of the speed of the press, is provided for operating the compensating lever to move the web into and out of contact with the moistening wick 12. This mechanically operated means includes a 80 governor 18 and the compensating lever 8, 9, operated thereby. The movable element 19 of the governor is connected to one arm 20 of a lever pivoted at 21, the other arm 22 of which lever is connected by a rod 23 to an 85 arm 24 of the compensating lever. The governor 18 is herein shown as operated through a train of gears 25, 26, 27, 28, 29, 30, 31, 32, 33, 34, driven by any suitable means, not shown, from the press. The 90 arm 22 of the lever 20, 22, is provided with an adjustable counterbalance weight 35 to hold the compensating lever 8, 9, normally in its position to keep the web out of contact with the dissipator. A ground wire 36 leads 95 from the fountain 13.

100 In operation, when the press and thereby the web is still, the governor holds the compensating lever in a position to bring the web out of contact with the moistening wick 12. As the press is started, it will when its speed reaches a predetermined point, operate the governor 18 to cause it to rock the compensating lever in a direction to bring the web 2 into contact with the 105 moistening wick 12. When the speed of

the press falls below a certain point, the web will be moved away from its contact with the wick.

It is obvious that the mechanically operated means shown herein for automatically bringing the web into and out of coaction with the dissipator is one of many different forms which might be shown for accomplishing this result; hence I do not wish 10 to limit myself to the particular means herein shown and described.

While I have shown this invention in connection with a running web, it is to be understood that I wish to include sheets 15 as well.

What I claim is:

1. A static electricity dissipator for webs including a moistener and mechanically operated means controlled by the speed of 20 the press for automatically moving the web into and out of contact with the moistener.
2. A static electricity dissipator for webs including a moistener normally out of contact with the web and mechanically operated means controlled by the speed of the press for automatically moving the web into 25 contact with the moistener.
3. A static electricity dissipator for webs including a moistener and mechanically

operated means controlled by the speed of the press for automatically moving the web into contact with the moistener when the web is running and out of contact with the moistener when the web is still.

4. A static electricity dissipator for webs 35 and mechanically operated means for automatically bringing the web and dissipator into and out of coaction, said means including a compensating lever having devices engaging the web for changing its 40 direction without changing its tension.

5. A static electricity dissipator for webs and mechanically operated means controlled by the speed of the press for automatically bringing the web and dissipator 45 into and out of coaction, said means including a compensating lever having devices engaging the web for changing its direction without changing its tension.

In testimony that I claim the foregoing 50 as my invention, I have signed my name in presence of two witnesses, this twenty-fourth day of April 1913.

HOWARD M. BARBER.
